UNITED STATES PATENT OFFICE.

ADOLFO DE CLAIRMONT, OF TOLEDO, OHIO.

ATTACHMENT FOR CARBURETERS.

1,033,386.

Specification of Letters Patent.

Patented July 23, 1912.

Application filed November 30, 1910. Serial No. 594,914.

To all whom it may concern:

Be it known that I, ADOLFO DE CLAIRMONT, citizen of the United States, residing at Toledo, in the county of Lucas and State of Ohio, have invented certain new and useful Improvements in Attachments for Carbureters, of which the following is a specification.

This invention comprehends certain new and useful improvements in attachments for carbureters as usually applied to internal combustion engines for automobiles or the like, and one of the main objects of my invention is a manually controllable auxiliary air valve arranged to furnish, at the will of the operator or driver, an extra supply of pure air to commingle with the charged gases from the carbureter, when the car reaches a predetermined speed. For instance, it is well known that a carbureter as now ordinarily constructed, while very efficient for relatively low speeds, furnishing a rich explosive mixture, is insufficient on relatively high speeds, owing to the fact that the suction created by four or six cylinders, is so great that the gasolene taken up is largely in excess of the requirements of the engine at high speed and the amount of air which is controlled automatically is not sufficient to dilute the mixture.

Hence it will be understood that it is one of the aims of my invention, by providing an auxiliary air valve controllable at the will of the operator, to save a considerable part of the gasolene at high speeds, to produce a better combustion in the cylinders and to thereby prevent the sooting and smoking which is usually caused by rich mixtures at high speeds. And the invention also has for its object a simple and efficient device of this character which is so arranged that it may be used effectively in starting the engine in cold weather or under such conditions as have heretofore required priming at the spark plugs, or priming cocks.

With these and other objects in view as will more fully appear as the description proceeds, the invention consists in certain constructions, arrangements and combinations of the parts that I shall hereinafter fully describe and claim.

For a full understanding of the invention, reference is to be had to the following description and accompanying drawings, in which:

Figure 1 is a vertical sectional view of my

improved carbureter, the section being taken substantially on the line 1—1 of Fig. 2; Fig. 2 is a horizontal sectional view, the section being taken on the line 2—2 of Fig. 1; and, 60 Fig. 3 is a perspective view of the device, illustrating an elbow that may be employed to secure the device to the side of the intake pipe of the main carbureter, instead of at the top thereof.

65 Corresponding and like parts are referred to in the following description and indicated in all the views of the drawings by the same reference characters.

70 My improved carbureter attachment comprises a casing 1 which is preferably substantially cylindrical, as shown, and which is provided at one end with a neck 2 exteriorly screw threaded or otherwise arranged so as to be connected to a carbureter 75 intake pipe. The upper end of the casing is provided with a preferably permanent top 3 formed with any desired number of preferably segmental slots 4 of any desired size, said slots being preferably equally 80 spaced from each other, and being controlled by a revoluble slide 5 which is mounted upon the top 3 and underneath a preferably detachable cover 3^a. The slide 5 and cover 3^a are provided with slots 6 corresponding in 85 number and preferably also in area to the slots 4, whereby the registering openings or slots in the top 3 and cover 3^a may be partially or fully open so as to admit into the casing 1 the required amount of air.

90 In the present embodiment of the invention, the revoluble slide 5 is provided with an outstanding handle 7, and a contractile spring 8 is secured at one end to said handle, the other end of the spring being secured to 95 a post 9 projecting outwardly from the casing 1, as shown. Manifestly, the tension of the spring 8 is exerted to normally hold the slide 5 in closed position, so as to completely cover the slots or openings 4 in the top 3 100 of the casing. The handle 7 may be operated in any desired way, from the dashboard or from any other point in convenient proximity to the driver or operator.

105 The casing 1 contains an open ended preferably cylindrical and longitudinally disposed tube 10 which is suspended intermediate of its ends from the top 3, the side walls and inner end of the tube 10 being spaced from the walls of the casing. The 110 upper end of the tube 10 may be closed by a screw cap 11 or any other desired form of

closure. The inner end of the tube is preferably closed by a screen 12, and the tube is designed to contain any desired number of cups 13 arranged in superposed relation to each other and resting one upon the other, the cups being adapted to hold absorbent material of any desired kind and being formed with screen bottoms 14. Preferably, the neck 2 of the casing is provided 10 with a screen 15 where it opens into the carbureter intake pipe.

From the foregoing description in connection with the accompanying drawing, the operation of my improved carbureter attachment will be apparent. When the device is connected to the intake pipe of the carbureter, the revolute slide 5 will be held in closed position so long as the engine is running at relatively low speeds; but when 20 higher speeds are attained, and it is desired to mix with the charged gases additional amounts or proportions of pure air, the handle 7 is manipulated to turn the slide 5 in a direction to open the slots 4, more or less, 25 as required, so as to admit into the casing and carbureter intake pipe, additional amounts of fresh air. By this means, it is obvious that the extra supply of pure air, which is controlled by the operator at will, 30 will mix with the charged gases from the carbureter, thereby reducing the consumption of the gasolene, producing a more efficient combustion in the cylinders and preventing the smoking and carbonizing which 35 is usually caused by rich mixtures at high speeds. It will also be seen that in the use of my device as an auxiliary air valve, it has the advantage of acting as a cylinder cleaner. For example, in coasting down a 40 hill, it is possible to shut off the throttle or gas valve, and by opening the auxiliary air valve to its fullest extent, fresh air may be introduced into the cylinders and effectively clean them out, the burned out gases, excess 45 of oil, soot and the like being expelled, all of which has a tendency to reduce the consumption of the gasolene and to cool the engine and clean the pistons.

As stated at the outset of the specification, 50 one of the objects of my invention is to produce a device of this character which may be used efficiently in starting a cold engine, in lieu of the ordinary priming methods. This function of the device is performed

practically by the tube 10 with its cups 13 containing absorbent material. In the practical use of the device for this purpose, the cap 11 is removed from the tube 10 and the absorbent material in the cups 13 is moistened by a predetermined amount of gasolene, whereupon by cranking the engine, the air will be drawn through the tube 10 and through the absorbent material in the cups 13, producing a properly saturated gas mixture acting in conjunction with the main 65 carbureter. After the engine or motor has been thus started, the cap 11 is again secured in place on the tube 10 so as to prevent the air from passing in through the tube.

It is obvious that it will be necessary to 70 use very little gasolene to moisten the absorbent material in the cups, and that the cups can be readily removed and cleaned and supplied with fresh absorbent material from time to time, as required.

As best seen in Fig. 3, the neck of the casing 1 may be provided with an extra elbow 2^a so that it may be secured to the side of the carbureter intake pipe instead of to the top of the same.

Having thus described the invention, what is claimed as new is:

A carbureter attachment, comprising a casing provided with a neck formed for attachment to the intake pipe of a carbureter, 85 the casing being also provided with a permanently attached top having openings formed therein, a tube disposed longitudinally and centrally in the casing and suspended therein by said top with the lower 90 end of the tube in spaced relation to the wall of the casing, a slotted revolute slide controlling the openings in the top, a plurality of cups supported in superposed relation to each other detachably in said tube, 95 and each formed with a screen bottom, absorbent material contained within said cups, a detachable closure for the outer end of the tube, the revolute disk being formed with an outwardly projecting handle, and a contractile spring connected to said handle and to the casing.

In testimony whereof, I affix my signature in presence of two witnesses.
